(57) CLAIM

The ornamental design for a removable storage deck for vehicles, as shown and described.

DESCRIPTION

FIG. 1 is a perspective view of a first embodiment of a removable storage deck for vehicles, shown from the top, one end, and one side, the opposite side being a mirror image of that shown;

FIG. 2 is a perspective view thereof, shown from the bottom, side, and the end opposite that shown in FIG. 1;

FIG. 3 is a perspective view of a second embodiment of the removable storage deck for vehicles, shown from the top, one end, and one side, the opposite side being a mirror image of that shown; and,

FIG. 4 is a perspective view thereof, shown from the bottom, side, and the end opposite that shown in FIG. 3.
